RETRACTING TYPE THEATER CHAIR

John J. Roman, Grand Rapids, Mich., assignor
to American Seating Company, Grand Rapids,
Mich., a corporation of New Jersey

Application August 2, 1946, Serial No. 687,935

6 Claims. (Cl. 155—116)

1

The present invention relates to chairs and more particularly to chairs of the retracting type for installation in theaters, auditoriums and the like. This application is a continuation-in-part of my co-pending application Serial No. 686,674, filed July 27, 1946.

The primary objects of the invention are to provide an improved chair of the retracting type wherein the chair occupant may move rearwardly in a sitting position in order to permit other theater patrons to pass in front of him; to provide such a chair which is of simple construction and which comprises few moving parts; to provide such a chair which may be easily and comfortably retracted and returned to forward position by the chair occupant; and in general to provide a retracting chair which is efficient in operation, reasonably economical in manufacture, and attractive in appearance.

An illustrative embodiment of the invention is shown in the accompanying drawings, wherein:

Figure 1 is a perspective view of a retracting chair in its forward position of occupancy;

Figure 2 is a sectional view of the same taken on line 2—2 of Figure 3;

Figure 3 is a fragmentary front elevational view showing the right hand side of the chair;

Figure 4 is a perspective view similar to Figure 1 and showing the chair in its rearwardly retracted position;

Figure 5 is a sectional view similar to Figure 2 and showing the parts of the chair in their rearwardly moved positions;

Figure 6 is a fragmentary side elevational view of the upper part of a chair supporting standard and showing a modified construction of the chair;

Figure 7 is a fragmentary rear elevational view of the same;

Figure 8 is a fragmentary top plan view of the same, a portion of the arm rest being broken away;

Figure 9 is a fragmentary side elevational view of the upper part of a chair supporting standard and showing another modified construction of the chair; and

Figure 10 is a fragmentary rear elevational view of the same.

Referring now in detail to these drawings, the retracting chair there shown is mounted upon a frame which comprises spaced, upright standards 10 which may be secured to the floor in any suitable manner and which are desirably connected by a suitable cross-tie 11. Arm rests 12 are mounted atop each standard 10 and secured thereto in conventional manner.

2

The chair proper generally comprises a seat and back assembly in which the chair seat 13 and the chair back 14 are pivotally connected for relative movement. The chair back 14 is mounted at its opposite sides on spaced back carriers 15 as by means of screws or rivets 16. The chair seat 13 is mounted on spaced seat carriers 17 at opposite sides thereof by means of brackets 18 secured to the seat 13 as by rivets 19 and which brackets 18 are pivotally connected at 20 to the seat carriers 17.

The rearward ends of the seat carriers 17 are pivotally connected at 21 to the lower, rearward ends or corners of the adjacent back carriers 15, thus connecting the seat and back in pivoted assembly.

The seat carriers 17 and back carriers 15 are mounted on the standards 10 by means of rear depending links 22 having their upper ends pivotally connected to the standards and their lower ends pivotally connected to depending rear legs 23 of the seat carriers 17. The seat and back assembly is thus supported in the rear for forward and rearward movements by the swingable depending links 22.

Intermediate depending links 24 support the back carriers 15 and back 14 forwardly of the rear links 22, said links 24 having their upper ends pivotally connected to the standards 10 and their lower ends pivotally connected to the forward parts of the back carriers 15. These swingable intermediate links 24 are of greater length than the distance between the pivotal connections of the links 22 to the standards 10 and the pivotal connections between the seat carriers 17 and the back carriers 15, and by this arrangement as the chair back is moved rearwardly it is also tilted to a near-vertical position thus to minimize the space required to the rear of the chair for retraction.

The forward portions of the seat carriers 17 and of the seat 13 are forwardly-rearwardly movably supported by swingable, depending front links 25 having their upper ends pivotally connected to the standards 10 and their lower ends pivotally connected to depending front legs 26 on the seat carriers 17.

It will be seen that as the chair is retracted by the occupant thereof, the seat moves rearwardly in a substantially straight path while the back moves rearwardly and is simultaneously turned to a near vertical position as seen in Figure 5. This rearward retracting movement is stopped by contact of the front links 25 with the cross-tie 11 of the frame. Forward, returning movement of the chair from its position shown in Figure 5 to

its position shown in Figure 2 is similarly stopped by contact of the depending rear legs 23 of the seat carriers 17 with the cross-tie 11.

It will be seen that the chair seat 13 may be folded upwardly to facilitate sweeping under the chair independently of its retracting and returning movements, by reason of its pivotal mountings on the seat carriers 17, and the seat is supported in its lowered, substantially horizontal position for occupancy by cooperating stops 27 on the brackets 18 and 28 on the seat carriers 17.

Figures 6-8 inclusive and Figures 9-10 illustrate two modified constructions designed to reduce the amount of work required to install chairs of this type in a theater and thus to reduce installation costs. In Figures 6-8, the upper ends of the links 22¹, 24¹ and 25¹ are pivotally connected to a mounting member 30 which fits into a recess 31 in the adjacent standard 10¹. The mounting members 30 of adjoining chairs which members are thus fitted into recesses 31 on opposite sides of a middle standard 10¹, are secured in place by means of a single bolt 32 passing through aligned apertures in the mounting members and the standard, and provided with a nut 33.

In Figures 9 and 10, the upper ends of the depending links 22², 24² and 25² are similarly pivotally connected to a mounting member 35 which fits into a recess 36 in the adjacent standard 10². The mounting members 35 of adjoining chairs which members are thus fitted into recesses 36 on opposite sides of a middle standard 10², are secured in place by means of a flanged plate 37 fastened as by screws 38 to the underside of the armrest 11². Inwardly turned flanges 39 on the plate 37 are slid into grooves 40 in the standards and 41 in the mounting blocks to thus secure these parts in assembly.

In either of the modifications above described, the depending links of the structure may be assembled to the mounting members 30 or 35 at the factory where costs are usually lower than at the place of installation. The chair units thus assembled may thereafter be readily installed on standards previously set in place in a theater or the like.

While but several specific embodiments of the invention have been herein shown and described, it will be understood that numerous details may be altered or omitted without departing from the spirit of the invention as the same is defined by the following claims.

I claim:

1. In a chair, a frame, a seat and back assembly wherein the seat and back are pivotally connected for relative movement, said pivotal connections being disposed rearwardly with respect to the frame and said seat and back having extensions forwardly of said pivotal connections, a pair of links swingably depending from the frame and pivotally connected to the rearward part of the seat and back assembly, a second pair of links swingably depending from the frame and pivotally connected to the forward extensions on the back, and a third pair of links swingably depending from the frame and pivotally connected to the forward extensions on the seat.

2. In a chair, a frame, mounting members adapted for attachment to the frame at the upper opposite sides thereof; a seat and back assembly wherein the seat and back are pivotally connected for relative movement, said pivotal connections being disposed rearwardly with re-

spect to the frame and said seat and back having extensions forwardly of said pivotal connections, a pair of links swingably depending from the mounting members and pivotally connected to the rearward part of the seat and back assembly, a second pair of links swingably depending from the mounting members and pivotally connected to the forward extensions on the back, and a third pair of links swingably depending from the mounting members and pivotally connected to the forward extensions on the seat.

3. In a chair, a frame, spaced seat carriers and back carriers arranged with a pivotally connected seat carrier and back carrier at each opposite side of the frame, said pivotal connections being disposed rearwardly with respect to the frame and said seat carriers and back carriers having portions extending forwardly of said pivotal connections, a seat mounted on the seat carriers, a back mounted on the back carriers, a pair of links swingably depending from the frame and pivotally connected at their lower ends to the rearward parts of the seat carriers, a second pair of links swingably depending from the frame and pivotally connected at their lower ends to the forwardly extending portions of the back carriers, and a third pair of links swingably depending from the frame and pivotally connected at their lower ends to the forwardly extending portions of the seat carriers.

4. In a chair, a frame, spaced seat carriers and back carriers arranged with a pivotally connected seat carrier and back carrier at each opposite side of the frame, said pivotal connections being disposed rearwardly with respect to the frame and said seat carriers and back carriers having portions extending forwardly of said pivotal connections, a seat mounted on the seat carriers turnably about a horizontal axis, cooperating stop means on the seat and the seat carriers for supporting the forward portion of the seat when the same is in a substantially horizontal position for occupancy, a back mounted on the back carriers, a pair of links swingably depending from the frame and pivotally connected at their lower ends to the rearward parts of the seat carriers, a second pair of links swingably depending from the frame and pivotally connected at their lower ends to the forwardly extending portions of the back carriers, and a third pair of links swingably depending from the frame and pivotally connected at their lower ends to the forwardly extending portions of the seat carriers.

5. In a chair, spaced chair-supporting standards, spaced seat carriers and spaced back carriers associated with said standards and having pivotal connections at their rearward ends, said pivotal connections being disposed rearwardly with respect to the standards and said seat carriers and back carriers having portions extending forwardly of said pivotal connections, a seat mounted on the seat carriers, a back mounted on the back carriers, and means for mounting the seat carriers on the standards for forward and rearward movements and the back carriers on the standards for forward and rearward movements and tilting movement about a horizontal axis, said means comprising rear links having their upper ends pivotally connected to the standards and their lower ends pivotally connected to the rearward ends of the seat carriers, intermediate links having their upper ends pivotally connected to the standards and their lower ends pivotally connected to the forward ends of the back

carriers, and front links having their upper ends pivotally connected to the standards and their lower ends pivotally connected to the forward ends of the seat carriers.

6. In a chair, spaced chair-supporting standards, spaced seat carriers and spaced back carriers associated with said standards and having pivotal connections at their rearward ends, said pivotal connections being disposed rearwardly with respect to the standards and said seat carriers and back carriers having portions extending forwardly of said pivotal connections, a seat mounted on the seat carriers turnably about a horizontal axis, cooperating stop means on the seat and the seat carriers for supporting the forward portion of the seat when the same is in a substantially horizontal position for occupancy, a back mounted on the back carriers, and means for mounting the seat carriers on the standards for forward and rearward movements and the back carriers on the standards for forward and rearward movements and tilting movement about a horizontal axis, said means comprising rear links having their upper ends pivotally connected to the standards and their lower ends pivotally connected to the rearward ends of the seat carriers, intermediate links having their upper ends pivotally connected to the standards and their lower ends pivotally connected to the forward ends of the back carriers, and front links having their upper ends pivotally connected to the standards and their lower ends pivotally connected to the forward ends of the seat carriers.
